United States Patent Office

Des. 197,766
Patented Mar. 24, 1964

197,766

SALES BOOTH

Dale F. Roxburgh, 5615 Northwest Drive, Omaha, Nebr.

Filed Sept. 25, 1963, Ser. No. 76,717

Term of patent 14 years

(Cl. D13—1)

The figure is a perspective view of a sales booth showing my new design.

The sides not shown are substantially mirror images of the sides shown. The top is flat and plain.

I claim:

The ornamental design for a sales booth, as shown and described.
